UNITED STATES PATENT OFFICE.

FRANK C. DE REAMER, OF BRIDGEPORT, CONNECTICUT, ASSIGNOR TO GENERAL ELECTRIC COMPANY, A CORPORATION OF NEW YORK.

ADJUSTING SCREW FOR PULL-CHAIN SOCKETS AND THE LIKE.

Application filed December 2, 1921. Serial No. 519,331.

The present invention relates to adjusting screws such as are used in pull chain lamp sockets to tension the actuator return spring, and has for its object to provide an improved screw which can be manufactured at a low cost and which will fit standard pull chain sockets as now manufactured.

For a consideration of what I believe to be novel and my invention, attention is directed to the accompanying description and the claims appended thereto.

In the drawing, Fig. 1 is a side elevation partly in section of a pull chain switch utilizing an adjusting screw embodying my invention; Fig. 2 is an exploded perspective view of the adjusting screw, return spring and actuator of the socket shown in Fig. 1; Fig. 3 is a bottom plan view of the adjusting screw; Fig. 4 shows the form a blank takes prior to being shaped to form the head of the adjusting screw; and Fig. 5 is an exploded perspective view of the two parts of the adjusting screw.

Referring to the drawing, 10 indicates a pull chain socket which as to its main features may have any suitable structure. 11 indicates the actuator which is given about a quarter turn by pulling on chain 12 to successively close and open the switch, the actuator being returned to its original position by retrieving on return spring 12. Return spring 12 is a coiled spring and has one end connected to actuator 11 and the other end to spring tensioning member 13. The spring tensioning member has a rectangular head which fits in a recess 14 in the top of the switch mounting block 15, and, in adjusting the spring, such member is pushed downward with a screw driver until the head is below the recess after which it is turned to give the desired tension to spring 12 and then permitted to come back to its original position with the head in the recess. This adjustment is well known in connection with pull chain sockets.

My invention relates particularly to the structure of the spring tensioning member 13. In the embodiment shown in the drawing, it comprises two parts, a head A and a body portion B, separately formed, and fastened together. Head A is formed of thin sheet material from a blank as shown in Fig. 4, and comprises a top wall 16 and side walls 17. Top wall 16 is pressed outwardly to

provide rounded portion 18 in which is a slot 19 adapted to receive the end of a screw driver. The sheet metal being thin, this rounded portion 18 is desirable in order to provide a slot sufficiently deep to give good engagement for a screw driver. Three of the side walls 17 are provided with inwardly projecting lugs or tongues 20 and the fourth is provided with a downwardly projecting hook 21 adapted to receive one end of spring 12. The manner in which a completed head is formed from a blank as shown in Fig. 4 is obvious from an inspection of Fig. 4 in connection with Figs. 3 and 5. Body portion B is in the form of an eyelet comprising a tubular shank 22 having a flange 23 at one end which is located within the side walls of head A and held by lugs or tongues 20, the latter lying under the flange as best shown in Fig. 3. The tubular shank is thus firmly fastened to the head. The body portion or eyelet B can be formed from thin material similar to that from which head A is formed.

When assembled in a socket, the hook at the upper end of spring 12, Fig. 2, engages hook 21 and the hook at the lower end of spring 12 engages a projection 24 on actuator 11, and it will be clear that turning member 13 in a clockwise direction as viewed from the upper end tensions the spring and turning it in the opposite direction relieves the tension on the spring. When being pushed down to bring head A out of recess 14 preparatory to turning member 13, the tubular body portion slides down on a post 25 which serves as a guide and support for the screw.

My improved adjusting member lends itself to being manufactured by automatic machinery from the minimum amount of stock and with very little waste material. As a result it can be made at a very low cost. At the same time it has ample strength and is thoroughly satisfactory for the purpose intended. Furthermore, due to the provision of hook 21, a tension spring 12 as shown particularly in Fig. 2 comprising a coil having similar hooks at its two ends can be utilized in the socket. The advantage of this is that a spring as shown including the hooks at the ends can be made on an automatic spring coiling machine, which means that the springs can be produced at the low-

est possible cost. In addition to this, the utilization of this type of spring expedites the assembling operations.

In accordance with the provisions of the patent statutes, I have described the principle of operation of my invention, together with the apparatus which I now consider to represent the best embodiment thereof, but I desire to have it understood that the apparatus shown is only illustrative and that the invention may be carried out by other means.

What I claim as new and desire to secure by Letters Patent of the United States, is:

1. An adjusting member comprising a polygonal head formed from sheet material, a separately-formed eyelet, and means formed integral with and comprising a part 20 of the head which means engages the eyelet to fasten the eyelet to the head.

2. An adjusting member comprising a polygonal head formed from sheet material, a separately-formed eyelet having a flange, 25 and means formed integral with the head and forming a part of the head which means engages said flange to fasten the head and eyelet together.

3. An adjusting member comprising a 30 head having top and side walls, a tubular eyelet having a flange located within the confines of said side walls, and inwardly projecting lugs and a hook carried by the side walls, said lugs serving to fasten the 35 eyelet to the head.

4. An adjusting member comprising a head having top and side walls, a tubular eyelet having a flange located within the 40 confines of said side walls, and inwardly

projecting lugs and a hook carried by the 40 side walls, said lugs serving to fasten the eyelet to the head, said top wall being provided with an outwardly projecting portion having a slot adapted to receive the end of a tool for turning the member. 45

5. An adjusting member formed from a sheet metal head and a flanged eyelet, said head having lugs for fastening it to the eyelet, a depending hook to receive the end of a spring, and a slot to receive the end of an 50 adjusting tool.

6. An adjusting member for use with a pull chain socket having an actuator, and a tensioning spring with a hook at each end, 55 said adjusting member being formed from a sheet metal head and a flanged eyelet, said head having fastening means for the eyelet and a hook with which the hook at one end of the tensioning spring is adapted to engage.

7. An adjusting member for a pull chain 60 socket or the like, said adjusting member comprising a polygonal head member formed from sheet material, an eyelet member, and fingers formed integral with one of said members and engaging the other member 65 to fasten them together.

8. An adjusting member for a pull chain socket or the like, said adjusting member comprising a polygonal head member formed from sheet material, an eyelet member having a flange, fingers formed integral 70 with the head which engages said flange to fasten the head and eyelet together, and means providing a hook which projects from said head member. 75

In witness whereof, I have hereunto set my hand this 29th day of November, 1921.

FRANK C. DE REAMER.
